Attorney

UNITED STATES PATENT OFFICE

ERASTUS C. STEPHENS, OF CANTON, GEORGIA, ASSIGNOR OF ONE-HALF TO STEVE E. SMITH AND ONE-HALF TO DAVID LEMON TURNER, BOTH OF PICKENS COUNTY, GEORGIA.

TERMINAL PULLER

Application filed December 1, 1928. Serial No. 323,167.

This invention relates to terminal pullers for use in removing the terminals of storage batteries, and more particularly to a device of this character which provides a means for engaging the terminal to pull the same which, at the same time, engages the post to provide leverage for the pulling action and wherein the pulling element may remain substantially stationary during the pulling operation except for motions imparted thereto by the post engaging element.

An important object of the invention is to provide a construction such that the puller may be engaged with the terminal at one side thereof only if but one side is accessible, and if both sides are accessible, may be engaged with both sides of this terminal, and in which one of the terminal engaging elements provided for use in the latter situation is so arranged that it may be moved to a position where it does not in any way interfere with the operation.

A still further object of the invention is to provide a device of this character which may be readily and cheaply produced, which may be durable and efficient in service, and a general improvement in the art.

These and other objects I attain by the construction shown in the accompanying drawings, wherein for the purpose of illustration is shown a preferred embodiment of my invention and wherein:

Figure 1 is a side elevation partially in section showing a terminal puller constructed in accordance with my invention in use for removing the terminal of a storage battery, the puller being illustrated as in use in a situation where both jaws can be engaged with a terminal in solid lines, the dotted lines indicating the position of the auxiliary jaw when this condition does not obtain;

Figure 2 is a transverse sectional view through the terminal puller, a terminal being indicated in dotted lines.

Referring now more particularly to the drawings, the numerals 10 and 11 designate handle members, of which the handle member 10 is provided, adjacent its lower end, with an angular extension 12 to which the handle element 11 is pivoted adjacent its

lower end, as indicated at 13. The pivotal connection is intermediate the ends of the angular extension and the lower end of the handle element 11 has an angular foot 14 extending in the same general direction as the free end of the angular extension. Pivoted to the angular extension is the lower end of a pressure bar 15, the upper end of which is connected with the handle member 11 by a link 16. The pivot 17 connecting the pressure bar to the angular extension is engaged in a slot 18 formed in the angular extension and extending longitudinally thereof, so that the lower end of the pressure bar may be adjusted toward and away from the handle member 11 and accordingly toward and away from the foot 14 to permit use of the device with the terminals of various sizes and connections of different sizes.

Above the link 16, the handle member has connected thereto at 19 the upper end of an arm 20 which has at its free end portion an angular foot 21 which, in one position of the arm, opposes the foot 14 of the handle member 11.

In the use of the apparatus, where the terminal to be removed is so located that a jaw can only be engaged beneath one side of the connector, the arm 20 is swung upwardly along the handle member and may be held in this position by grasping it simultaneously with the handle member. By moving the handle members 10 and 11 toward one another, the lower end of the pressure bar 15 is brought into engagement with the upper surface of the battery post P and application of pressure will result in upward pressure upon the connector C. By vibrating the pull while maintaining this pressure, the connector may be readily removed. Where both sides of the connector are accessible, the arm 20 is swung downwardly so that both feet 14 and 21 engage beneath the connector and the handle members are moved toward one another.

Since the construction hereinbefore set forth is capable of a certain range of change and modification without materially departing from the spirit of the invention, I do not

limit myself to such specific structure except as hereinafter claimed.

I claim:—

1. In a terminal puller, a handle member having at its lower end an angular foot, a second handle member having an angular extension, said angular extension being pivoted to the first named handle member above the foot and in spaced relation thereto and having an end extending outwardly over and beyond the foot, a link pivoted to the first named handle member above said extension and paralleling said extended end thereof, and a pressure bar pivoted at its upper end to said link and at its lower end to the said end of the extension.
2. In a terminal puller, a handle member having at its lower end an angular foot, a second handle member having an angular extension, said angular extension being pivoted to the first named handle member above the foot and in spaced relation thereto and having an end extending outwardly over and beyond the foot, a link pivoted to the first named handle member above said extension and paralleling said extended end thereof, and a pressure bar pivoted at its upper end to said link and at its lower end to the said end of the extension, the connection of the pressure bar with the extension being adjustable longitudinally of the extension.
3. In a terminal puller, a handle member having at its lower end an angular foot, a second handle member having an angular extension, said angular extension being pivoted to the first named handle member above the foot and in spaced relation thereto and having an end extending outwardly over and beyond the foot, a link pivoted to the first named handle member above said extension and paralleling said extended end thereof, a pressure bar pivoted at its upper end to said link and at its lower end to the said end of the extension, and an arm pivoted to the first named handle member above the link and having at its free end an angular foot which in one position of the arm aligns with the foot of the first named handle member in spaced opposition thereto.
4. In a terminal puller, a handle member having at its lower end an angular foot, a second handle member having an angular extension, said angular extension being pivoted to the first named handle member above the foot and in spaced relation thereto and having an end extending outwardly over and beyond the foot, a link pivoted to the first named handle member above said extension and paralleling said extended end thereof, a pressure bar pivoted at its upper end to said link and at its lower end to the said end of the extension, and an arm pivoted to the first named handle member above the link and having at its free end an angular foot which in one position of the arm aligns with

the foot of the first named handle member in spaced opposition thereto, the connection of the pressure bar with the extension being adjustable longitudinally of the extension.

In testimony whereof I hereunto affix my signature.

ERASTUS C. STEPHENS.
